UNITED STATES PATENT OFFICE

JAMES M. KANE, OF BERKELEY, CALIFORNIA

SIGNALING SYSTEM

Application filed March 13, 1931. Serial No. 522,483.

(GRANTED UNDER THE ACT OF MARCH 3, 1883, AS AMENDED APRIL 30, 1928; 370 O. G. 757)

My invention relates broadly to telegraphic signaling systems and more particularly to high speed telegraphic signaling systems having means for eliminating interference from static and other interfering signals.

One of the objects of my invention is to provide a signaling system in which the effects of static and interfering signals may be substantially reduced and signal receiving circuits operated through such static and interference.

Another object of my invention is to provide a telegraphic receiving circuit having means for operating a relay for reproducing transmitted telegraphic signals irrespective of static and other interference, even under conditions where the static and interference may be of relatively large amplitude and of such a character as to render the operation of other types of receiving systems impractical as heretofore known.

Still another object of my invention is to provide an arrangement of electron tube circuits adapted to be connected to the audio frequency output of a radio receiving system and operating a signal receiving relay wherein the electron tube circuits balance out the effects of static and interfering signal energy while amplifying the desired signaling energy and positively actuating the relay.

A further object of my invention is to provide an audio frequency amplifier system having a pair of independent branches with a relay including a pair of actuating windings, one of said windings being in magnetic association with each of said branches with means for balancing the effects of static and interfering signaling energy while amplifying the effects of the signaling energy for operating said relay system without interference from the static and undesired signaling energy.

Other and further objects of my invention reside in the arrangement of branch circuits of an amplifier and relay system as set forth more fully in the specification hereinafter following by reference to the accompanying drawing which diagrammatically illustrates

the amplifier and relay system of my invention.

A single frequency can be rejected from a circuit with greater facility than a single frequency can be accepted with all others both above and below rejected. Hence it is proposed to provide two branch circuits, one of which substantially entirely rejects the signal frequency yet transmits readily all of the other frequencies comprising the interference, and the other branch circuit of which transmits readily the signal frequency yet rejects in part the frequencies comprising the interference. The output of the branch that transmits the interference frequencies alone and the output of the branch that transmits the signal frequency and some of the interference frequencies are brought together in phase opposition to effect the balancing out or neutralization of the interference frequencies, while permitting the signal frequency alone to affect the recording device.

The circuit arrangement of my invention is based upon the selective audio tuning of a pair of branch circuits associated with the output of the audio frequency amplifier in a signal receiving system by which undesired static energy and interfering signal energy may be eliminated. The system of my invention comprises an amplifier having an input stage adapted to resolve the incoming signal voltage into two components and selectively amplify these components in separate branches of the amplifier system. One branch is arranged to amplify all the variations in the input voltage at the terminals of the audio frequency amplifier except the variations in the voltages of the desired signal energy. The second branch is arranged to amplify the desired signaling energy as much as possible, together with such other voltages that pass through the audio tuning filters. The first branch circuit is coupled through an audio frequency amplifier to a circuit whose output is controllable, connections being provided between such circuit and a vacuum tube system whose grid is driven positive by an increase in energy through the first branch circuit. In other words, as the amplitude of the undesired sig-

naling energy, static and interference, increases the average plate current through the control tube circuit tends to increase. In the second branch circuit, in which the desired signal energy and interference is amplified, a coupling is provided to the grid of the same electron tube that is controlled by the first branch circuit though in such manner that any voltage in the second branch will tend to decrease the average plate current through the tube. Summarizing the above general statements, any tendency that the interference voltage may have to increase the plate current through the control tube will be offset by the tendency of the voltage in the second branch to decrease the same plate current. By accurate adjustment of voltage values the resultant change of plate current through the control tube due to interference contained in each of the branches will be zero. The desired signal in the second branch generating no counter-force in the first branch will cause a change of plate current in the control tube and the actuation of the relay system for the closing of a control circuit to any desired recorder, such as a teletype automatic printer or ink register.

Referring to the drawing in detail, reference character 1 designates an input audio frequency transformer having a primary winding 2 and a secondary winding 3, the primary winding 2 being connected through terminals 1a and 1b with the output of an audio frequency amplifier system of a signal receiving apparatus. A power amplifier tube 4 is provided to receive all of the audio frequency signal components and the static and interfering energy components and increase the amplitude thereof. The output of the power amplifier tube 4 is connected to two independent branch circuits through separate transformers 6 and 7. Transformer 6 has its primary winding 8 coupled with its secondary winding 9. The primary winding 8 has the primary winding of a second transformer 10 shunted there-across, across the secondary of which is connected a variable condenser 11 to tune this winding thereby making it operate to reject from the first branch circuit the desired signal components while selectively responding to the undesired signal components. The output of the transformer 6 is connected to the input of electron tube 12 which includes meter 14 in the output circuit thereof, the output of tube 12 being coupled through transformer 15 with the input of the succeeding tube 16. The amplitude of the undesired signaling energy, static and interference, is increased by the amplification characteristics of tubes 12 and 16 and delivered through transformer 17 to the output control circuit which I have designated generally at 18. The output control circuit includes a variable resistor 19 connected in shunt with the secondary winding

20 of the transformer system 17 and in series with the potentiometer control circuit designated at 21. The potentiometer control circuit includes the battery 21a and the shunt connected resistor 21b arranged as shown for effecting the required adjustment of grid potential on control tube 22. The control tube 22 includes cathode 22a, control grid 22b and anode 22c. The control grid 22b is connected to one terminal of the control circuit 18. The output of the control tube 22 includes the winding 23 of the polarized relay system 24 in which the actuating winding 25 is arranged adjacent the winding 23 for controlling the operation of the armature 26 in the field of the permanent magnet system 27. Armature 26 operates the moving contact system 28 for establishing connection with fixed contacts 29 and 30. The control tube 22 operates with a high plate current obtained from the source 31. A greater voltage will be required to increase the current than will be required to decrease the current in the output circuit of the control tube. Consequently the tube 16 and the transformer shunt 19 are necessary to permit the adjustment of the interference voltage in the first branch circuit to such a value that its effect in the plate circuit of tube 22 offsets the applied in the opposite direction by the control tube 32 in the second branch circuit.

The control tube 32 in the second branch circuit includes a cathode 32a, a control grid 32b, and an anode 32c. The input circuit of the control tube 32 is completed through the secondary winding 33 of the transformer 7 constituting a part of the second branch circuit in the output circuit of the power amplifier tube 4. The transformer 7 has its primary winding 34 connected to a transformer system 35 in which one winding thereof is shunted by means of a tuning condenser 36 which serves with the transformer system 35 as an audio frequency filter by means of which the interference, static and undesired signaling components, are rejected from the second branch circuit permitting the second branch circuit to respond to the desired audio frequency signal. By manipulation of the rejector 35-36 the second branch circuit may be made to respond to the desired signal excluding undesired signaling energy and static while manipulation of the filter constituted by transformer 10 and condenser 11 enables the first branch circuit to respond to the undesired signaling energy, static, and interference to the exclusion of the desired signaling energy. The input circuit of the control tube 32 in the second branch circuit is completed by means of a tap 37 on potentiometer 38 which is connected in shunt with the source of biasing potential 39, a connection returning from the biasing circuit through lead 40 to the cathode 32a of the control tube 32. The biasing potential source 39

also has a potentiometer 41 connected in shunt thereto over which tap 42 is adjustable for varying the potential of the grids of each of the tubes 4, 12 and 16 constituting the 5 amplification system for the first branch circuit. The cathodes of each of the tubes 4, 12, 16 and 32 are heated from the source of potential designated as 43.

The output circuit of the control tube 32 10 includes the meter 44, the winding 25 of the polarized relay 24, the impedance or resistor 45, and the high potential source 46. The plate potential for the tubes 4, 12 and 16 is obtained through connection 47 to the point 15 48 in the output circuit of the control tube 32 adjacent the high potential source 46. The cathode 22a of the control tube 22 is heated from a separate potential source indicated at 49. In the particular arrangement 20 illustrated, I have shown the control leads of the relay system brought out to the marking, spacing and timing terminals 50, 51 and 52 leading to the fixed contacts 29 and 30 and movable set of contacts 28 as shown. The 25 windings 23 and 25 of the relay system 24 operate conjointly upon movable armature 26 for effecting the positive closing of the contacts without interference from static and undesired signaling energy.

30 It will be observed that the input circuit of the control tube 22 is completed through a portion of the output circuit of the control tube 32, that is to say, the control grid 22b connects to the end of the secondary winding 35 20 of the transformer 17, the opposite end of which is connected through slidable contact 21c on potentiometer 21b to the point 54 in the output circuit of control grid 32. The connection 54 is immediately adjacent one 40 end of the impedance or resistance 45, the other end of which at 55 is connected through lead 56 to the cathode 22a for completing the input circuit connections to the tube. This arrangement provides for the raising of 45 the average grid voltage on control grid 22b when input signal energy is received in the first branch circuit. The raising of the average grid voltage on grid 22b results in an increase of the average plate current in 50 the output of control tube 22. Any tendency the interference voltage may have to increase the plate current in tube 22 will be offset by the tendency of the interference voltage in the second branch circuit to decrease the 55 same plate current. By accurate adjustment therefore the effect of the interference in the two branch circuits will be zero. However, the desired signal contained in the second branch circuit having no counterforce in the 60 first branch circuit will cause a change of plate current and effect an operation of the relay system.

The apparatus of my invention is first adjusted prior to the reception of telegraphic 65 signals by disconnecting the apparatus at

terminals 1a and 1b from the audio frequency amplifier system of the signal receiver. The bias potential on control grid 32b of control tube 32 is adjusted by movement of contact 37 on potentiometer 38 so that meter 44 in the output circuit of control tube 32 reads zero. The bias potential on the grid 22b of tube 22 is adjusted by movement of contact 21c on potentiometer 21b until the meter 53 in the output circuit of control tube 22 reads a 70 predetermined calibrated value. I have selected for this reading three milliamperes in an apparatus which I have successfully constructed and operated. After completing these adjustments the input terminals 1a and 1b of the relay system are connected to signal receiving apparatus. The filter circuit constituted by transformer 10 and variable condenser 11 is then adjusted by moving the audio tuning control at 11 whereby the desired signal is eliminated from the first branch circuit while permitting the passage 80 of the undesired signal, static, and interfering signaling energy. Under this condition the meter 14 in the output circuit of tube 12 in the first branch circuit responds only to interference.

By adjustment of the audio frequency tuning control constituted by the variable condenser 36 which is connected to the audio frequency transformer system 35, the interference, including static and undesired signal is somewhat suppressed enabling the second branch circuit to respond to the desired signaling energy at its maximum so that the 85 meter 44 of the control tube 32 responds to the desired signaling energy. By manipulation of the transformer shunt 19, the circuits are adjusted until an equal amplification of interference is obtained in each circuit. Under 90 this condition the relay armature 26 will respond to the desired signaling energy alone, thus operating the contact system and controlling the circuits to terminals 50, 51 and 52 which may be connected to a teletype 95 printer or other form of recording apparatus.

The amplification afforded by tube 16 and the adjustment provided by transformer 115 shunt 19 serves to bring the interference voltage in the first branch circuit to such a value that its effect in the plate circuit control of tube 22 will offset the effect of the interference existing in the circuit of control tube 32. It will be observed that the opposite effect of the interference is not due to any magnetic reaction of one field upon another with a view of canceling the effect of such fields. The interference is actually separated into two independent circuits each of 120 which connect to the relay windings 23 and 25. However, the interference will have no effect upon the movement of the relay armature 26 as the amplitude of the interfering effects will be the same in both relay wind- 130

ings. The signal energy however which is totally absent in the first branch circuit is effective in the second branch circuit to operate the relay armature 26.

5 Adjustments of this circuit are relatively simple. The milliameters are used as indicators rather than the usual headphones, for when using the latter it is difficult to note an exact resonant condition because of the 10 large currents encountered. The milliameters are better indicators of resonance than headphones.

To show the facility with which this circuit can cancel out interference, tune the second branch circuit to the frequency of the desired audio signal. With a local audio oscillator being controlled by contacts 50 and 15 51 and reproducing the modulations of the desired signal, tune the first branch circuit 20 to the same frequency as the second branch circuit. The action of the relay will cease, and the meter 53 of tube 22 will show no change of current, signifying that the voltages applied to the grid of tube 22, via transformer 17 and resistance 45 are equal in potential and 180 degrees out of phase.

The principle of operation of my invention may be clearer by considering the control tube 22 as a "holding over tube" while 30 the control tube 32 may be considered as the signal tube. Because of the interlinking of the input circuit of the holding over tube 22 with the output circuit of the signal tube 32, a rise of plate current in the output of the 35 signal tube 32 due to an incoming signaling impulse operates to decrease the current in the plate circuit of the holding over tube 22. However, the interference and static energy incident upon the input circuit of the holding 40 over tube 22 tends to increase the plate current. The actual plate current through winding 23 is therefore a differential between the desired signal energy and the integrator of the undesired signal energy and 45 static. Because of the fact that the signal persists in addition to and separate and distinct from the interference, the signal energy will actuate the relay armature 26 and effect the positive closing of the control circuit.

50 In the operation of the circuit of my invention the received audio frequency energy is split into two paths with interference in only one path. This interference causes the grid 22b of tube 22 to assume a positive 55 charge through transformer secondary 20. This positive charge on grid 22b would cause plate current through 22 to increase were it not for the desired or signal energy coming through tube 32 along with interference. 60 These two voltages are so combined by means of resistance 45 that they produce a negative potential on the grid 22b of tube 22. The negative potential on the grid 22b from tube 32 consisting of interference is offset by the 65 interference having a positive potential com-

ing from tube 16 via transformer secondary 20. These two voltages of opposite polarity, then, cancel out and no plate current charge through tube 22 results from interference. The negative voltage coming from tube 32 70 consisting of desired signal finds no counter voltage of an opposite polarity from tube 16 and transformer secondary 20, so the negative signal voltage decreases the potential of grid 22b causing a decrease of plate current through tube 22 and coil 23, coincident with an increase of current through tube 32 and coil 25. Thus coil 25 operates the relay arm until the signal through tube 32 decreases coincident with an increase of current through tube 22 and coil 23, when 23 operates the arm 28.

I have found the apparatus of my invention particularly useful in high speed telegraphic signal receiving systems where considerable interference from static and undesired signals is experienced.

Under conditions of relatively heavy static and considerable interference, I have succeeded in successfully operating automatic printing apparatus and other forms of recorders for continuous traffic over extended periods. The apparatus of my invention responds to the rapid fluctuations in signal voltage such as represented by the Baudot 95 code of printing telegraph systems, and accordingly is highly useful as a connecting link between the radio receiving apparatus and the automatic printing apparatus of a high speed radio telegraph system.

100 While I have described my invention in one of its preferred embodiments, I desire that it be understood that modifications may be made and that no limitations upon my invention are intended other than are imposed by the scope of the appended claims.

The invention described herein, if patented may be manufactured and used by or for the Government for governmental purposes without the payment to me of any royalty 110 thereon.

What I claim as new and desire to secure by Letters Patent of the United States is as follows:

1. In a signal receiving system, an input 115 circuit, a pair of branch circuits extending from said input circuit, one of said branch circuits having means discriminating against the desired signaling energy while transmitting undesired signaling energy and interference and the other of said paths having means discriminating against interference and undesired signaling energy while transmitting the desired signaling energy, a pair of control tubes each having input and output circuits with the input circuits thereof individually connected to each of said paths, a relay system including a movable armature and a pair of actuating windings, means interconnecting the output circuit of each con- 130

trol tube with a selected winding, a resistance element included in the output circuit of one of said control tubes and connections across said resistance element with the input circuit of the other of said control tubes for differentially energizing said control tubes for effecting a balancing operation of said actuating windings with respect to the undesired signaling energy and interference
10 while controlling the movement of said armature under control of the signaling energy.
2. In a signal receiving system, an input circuit, a pair of branch circuits extending from said input circuit, one of said branch circuits having means discriminating against the desired signaling energy while transmitting undesired signaling energy and interference and the other of said paths having means discriminating against interference and un-
15 desired signaling energy while transmitting the desired signaling energy, a relay system including a movable armature and a pair of actuating windings, a pair of control tubes each having input and output circuits, a
20 control grid in each of said control tubes, the output circuit of one control tube including one of said actuating windings and the output circuit of the other of said control tubes including the other of said actuating wind-
25 ings, the input circuit of said first mentioned control tube being connected to said first mentioned branch circuit, the input circuit of the other of said control tubes being connected with the other of said branch circuits
30 and connections between the output circuit of said last mentioned control tube with the input circuit of said first mentioned control tube for producing a current drop in the output circuit of said first mentioned control
35 tube due to the impression of signaling energy upon the control grid of said second mentioned control tube for opposing an increase of output current in said first mentioned control tube due to the impression of
40 undesired signaling energy and interference
45 on the input circuit thereof for effecting movement of said armature under control of the signaling energy.
